UNITED STATES PATENT OFFICE.

CHARLEY KOWALSKI, OF CHICAGO, ILLINOIS.

DESIGN FOR A FERNERY STAND.

Application filed March 2, 1925. Serial No. 12,539. Term of patent 7 years.

To all whom it may concern:

Be it known that I, CHARLEY KOWALSKI, a citizen of Poland, residing at Chicago, in the county of Cook and State of Illinois, have invented a new, original, and ornamental Design for Fernery Stand, of which the following is a specification, reference being had to the accompanying drawing, forming a part hereof.

In the said drawing—

stand embodying my new design.

Figure 2 is a perspective view of the same.

I claim:

The ornamental design for a fernery stand, as shown.

In witness hereof I hereunto affix my signature this eighteenth day of February, 1925 A. D.

CHARLEY ^{his} X KOWALSKI.
